BY
Robert Killgore
ATTORNEY

UNITED STATES PATENT OFFICE.

WINFIELD D. SMITH, OF DEAL, NEW JERSEY, ASSIGNEE TO LOUIS G. SYLVESTER, OF SCRANTON, PENNSYLVANIA.

SYSTEM AND APPARATUS FOR PRODUCING SOUND.

Application filed October 8, 1927. Serial No. 224,986.

My invention relates to a system and apparatus for producing sound from electrical impulses created by a plurality of musical instruments and it is my object to produce a system and apparatus by means of which the musical instruments such as were used in making the sound may be replayed by the electrical impulses thereby producing a complete recreation of the original sounds.

10 In the drawing Fig. 1 is a diagrammatic representation of the apparatus used for replaying a simple combination of the instruments used in making a sound record; and Fig. 2 a diagrammatic representation of a 15 slightly modified form of my invention. It is apparent that the principles involved may be applied to any kind or number of musical instruments played in ensemble or to any sounds,

20 For the purpose of disclosing my invention I will take a talking machine record 1 having thereon a sound groove made by a brass quartette, composed of a cornet, a trumpet, a 25 trombone and an alto horn. This record is revolved in the usual manner by any suitable mechanism. Engaging the sound groove is a generating transmitter 2 of the type shown in my co-pending application Ser. No. 77,329, filed December 23, 1925, by means of which 30 the recorded sound waves are converted into electrical impulses corresponding thereto. This current is then fed through an audio amplifying device 3 of any desired type. The cornet 4, trumpet 5, trombone 6 and alto 35 horn 7 each has, in lieu of its regular mouthpiece, a telephone receiver 8 of the type used in radio loud speakers. These receivers are all connected to the output side of the audio amplifier 3.

40 When the record is revolved the generated electrical impulses are amplified and fed to the receivers 8. As each instrument has an air column of determined or fixed characteristics it will strongly amplify the audio frequencies on the record which come within the range of its air column. The audio frequencies outside the characteristics of the air column will be feebly, if at all, reproduced by that instrument. In other words, the cornet will strongly 45 produce the cornet sounds, the trumpet will strongly produce the trumpet sounds, the trombone will strongly produce the trombone sounds and the alto horn will strongly produce the alto horn sounds, due to the sympathetic vibrations of the air columns. As the

instruments (or fac-similes of them) which made the record are used in recreating, the audio results will be the same as the original playing, due to the fact that air columns of the same characteristics and sympathetic vibrations, enclosed in the same materials, are used. It should be noted that perfect recreation in those instruments having adjustable valves will be more truly resonant to pitch when the air columns have been so matched.

50 Any desired instrument, or combination of instruments, may be played from a record of them. It is also possible to design a battery of horns, each having an air column corresponding to the air column of the instrument 55 to be strongly amplified, and preferably made of the same material as the original instrument, which will perform the functions of the instruments themselves.

As shown in Fig. 2 a single loud speaker 75 unit 9 may be connected to the plurality of horns or instruments and the air columns will vibrate in sympathy with the recorded notes on the record thereby reproducing them with the utmost fidelity.

60 I am aware that a plurality of loud speakers have been attached to and operated from a single sound record but so far as I am aware I am the first to use a plurality of instruments (or fac-similes thereof) having consequently 65 the same audio vibratory characteristics as the instruments used in making the sound record and actuating them simultaneously to accurately recreate the sounds originally recorded.

70 I claim:

1. A sound producer comprising a talking machine record made from a plurality of musical instruments, a generating transmitter for converting the recorded sound waves into electrical impulses, an audio amplifier, a plurality of telephonic receivers and musical instruments such as were used in originally 75 making the sound record, each of which is separately operatively connected with a telephonic receiver.

80 2. A sound producer comprising a talking machine record made from a plurality of musical instruments, a generating transmitter for converting the recorded sound waves into electrical impulses, an audio amplifier, a plurality of musical instruments each matching 105 in size, shape and material and having the characteristics of the air column of an instrument used in originally making the sound rec- 110

ord, and a telephonic receiver separately operatively connected to each air column whereby each air column accurately recreates its corresponding instrument used in making the original sound record.

3. The method of producing sound consisting in generating electrical impulses corresponding to the playing of a plurality of musical instruments, amplifying said impulses 10 and finally recreating them through a plurality of musical instruments having the same audio vibratory characteristics as the instruments creating the electrical impulses.

4. A sound producer comprising apparatus for converting sound waves produced by a plurality of musical instruments into corresponding electrical impulses, an audio amplifier, a plurality of telephonic receivers and musical instruments having the same audio vibratory characteristics as those used in generating the electrical impulses operatively connected with the receivers. 20

In testimony whereof I have affixed my signature.

WINFIELD D. SMITH.
